UNITED STATES PATENT OFFICE.

EDWARD SMULSKI, OF NEWTON HIGHLANDS, MASSACHUSETTS.

REINFORCED CONCRETE CONSTRUCTION.

1,154,548.

Specification of Letters Patent. Patented Sept. 21, 1915.

Application filed January 8, 1913. Serial No. 740,763.

To all whom it may concern:

Be it known that I, EDWARD SMULSKI, a subject of the Emperor of Austria-Hungary, and a resident of Newton Highlands, county 5 of Middlesex, State of Massachusetts, (whose post-office address is 809 Oliver Building, Boston, Massachusetts,) have invented an Improvement in Reinforced Concrete Construction, of which the following 10 description, in connection with the accompanying drawings, is a specification, like characters on the drawings representing like parts.

This invention relates to reinforced concrete construction consisting more particularly of an improved system of reinforcement for slabs and especially floor slabs.

The invention will be best understood by reference to the following description when taken in connection with the accompanying illustration of one specific embodiment thereof, while its scope will be more particularly pointed out in the appended claims.

In the drawings, Figure 1 is a plan view 5 of the system of reinforcement which may be employed in a floor slab embodying one form of my invention; Fig. 2 is a sectional elevation taken on the line 2-2 in Fig. 1; and Fig. 3 is a similar sectional elevation 30 taken on the line 3-3 in Fig. 1.

Referring to the drawings and to the embodiment of my invention there submitted for illustrative purposes, while the latter may be applied to a slab of non-uniform 35 thickness, or to a slab which is indented or has portions cut out, I have herein shown the same as applied to a flat floor slab 1 of uniform thickness supported by columns 2 having the flaring caps 3 and having no 40 beams or girders. The reinforcement for the slab is arranged in such a way that the direction of the reinforcing members coincides with the direction of the stresses in the slab. The reinforcing members are concentrated at points of greatest stress and their size and number depend upon the magnitude of the bending moment.

Referring to the drawing, and particularly to Figs. 1 and 2, the floor slab immediately over each column is provided with a series of reinforcing members 4 radiating or diverging from the axis of the column.

These may be of any suitable material or shape, but are preferably in the form of steel rods. These rods diverge from the column adjacent the upper surface of the slab so

that they take the tensile stress due to the bending moment of the slab.

The full strength of the rods may be developed by a bond between the steel and concrete or by anchoring the inner end of each rod. For this purpose any suitable anchorage formation may be provided upon the rods as by bending over the inner ends thereof. As shown in the drawings, the rods are carried over the top of the column and each rod is bent thereat into the form of a suitably shaped and proportioned hook. The inner ends of the rods may be attached to each other or to a common anchorage member, such member being herein provided by the ring 5 with which the hooked ends of the radial rods 4 engage. The bent end 6 of each rod may be prolonged as shown so as to extend adjacent the lower surface of the slab and serve as compression reinforcement thereat. The weight of the slab or a load thereon produces a strong compression in the region of the concrete at the juncture of the slab with the column tending to rupture or injure the concrete in said region. This, however, is effectively prevented by the presence therein of the bent ends 6 of said rods. The purpose of the inner ring 5 is primarily to keep the inner ends of the radial bars in position during concreting and also to add an additional factor of safety by removing even a remote danger of splitting the concrete. Actual contact in the concrete between the ring and the hook of the radial bars is not required and such contact is obtained in practice with difficulty and only with close supervision. The anchorage of the bars relied upon is that developed by bond and bearing in the concrete. The bend 95 of the hooked bars is placed from the point of maximum stress, that is the edge of the column head, a sufficient distance to develop in combination with the hook the full strength of the bar and the stress of the 100 hooked bars is directly transferred to the concrete by bond and bearing. In designing the inner rings are arranged in such a way that the radial bars are not relied upon until their full strength is developed by embedding 105 in the concrete and the hook.

The radial rods 4 are designed to resist the radial bending moment of the slab. To resist the circumferential moment, circumferential reinforcing members 7 are provided transverse the radial members 4 and also near the upper surface of the slab. The

circumferential members 7 may be in the form of straight rods, but herein are shown as annular or circumferential in form.

Referring now to the panel reinforcement, the latter is provided by means of a series of rods 8 which radiate or diverge from a central or intermediate point in the panel, and preferably substantially the point of greatest stress, toward the reinforcement at and above the adjacent columns. The panel reinforcement is located near the lower face of the slab as shown so as properly to take the tensile stress thereat. The panel reinforcing rods 8 are also securely anchored near the center of the panel so as to develop their full strength. Their anchorage may be provided in any desired manner, but herein their inner ends are bent each into the form of a hook 9 and caused to engage an anchoring ring 10, which latter securely holds them in position. The other end of each rod may be straight or bent and carried into the upper part of the slab if desired.

In order to resist circumferential moments in the slab transverse reinforcing members are employed, also near the lower surface of the slab. At the left of Fig. 1 these are shown to consist of circumferential rods 11 combined with straight rods 12, but instead of the circumferential rods, straight rods 13 may be used as shown at the right of Fig. 1. The size and number of the reinforcing members in each case will, of course, be designed with reference to the magnitude of the bending moment to be encountered. By diverging reinforcing members I do not necessarily mean those which are arranged in a true radial relation, but intend to include such an arrangement of reinforcement as tends to concentrate the same near the point of greatest stress in the panel.

The described form of reinforcement possesses great advantages over forms heretofore prevailing. A surplus of metal is avoided since the rods occur only where needed and in the amount needed. That is to say, their diverging arrangement naturally concentrates them at points of greatest stress. The principal bars being arranged in one layer only, the effective depth of a slab having a given thickness is greater than where multiple layers are employed. Furthermore, the total sectional area of the steel is effective in resisting the stresses.

As indicated in the drawings, the ring 5 is preferably larger than the diameter of the column so as to leave at the column an open space between the slab reinforcement and the column reinforcement. The purpose of this is to permit the cleaning of the column head form after the concrete in the column has been poured. It is a well known fact that the top of the concrete after setting be-

comes covered with scum and laitance, or decomposed cement. Other impurities and dirt also find their way into the column head form in the interval between placing the steel and pouring the slab concrete. For good work the laitance and impurities should be removed. In systems where a mesh of bars is placed over the column or where reinforcements extend as far as the column steel, cleaning of the column form-work is difficult if not impossible. In the disclosed system, the form-work is easily accessible and no difficulty is encountered from cleaning. The disclosed system also requires less steel since every radial bar is shorter by the difference in the radius of the circuit around which they stop and the radius of the column.

While I have herein shown and described for purposes of illustration one specific form of the invention and applied to a floor slab, it is to be understood that the same is not limited to the details of construction and specific form and relative arrangement of parts herein described, or to its application to a floor slab, but that it may be applied to constructions other than floor slabs, and extensive deviations may be made from the illustrative embodiment without departing from the spirit of the invention.

Claims.

1. In a concrete slab construction, the combination with a supporting column of reinforcing members diverging from the axis of the column, each of said members having a reverse bend near the column and presenting a portion near the upper surface of the slab, and a portion near the lower surface of the slab extending across and serving as a compression reinforcement for the juncture of the slab with the column.

2. In a concrete slab construction, the combination with a supporting column of reinforcing members diverging from the axis of the column, each of said members having a reverse bend near the column and presenting a tension reinforcement near the upper surface of the slab, and a compression reinforcement portion near the lower surface of the slab, said reverse bend having a depth substantially greater than the thickness of the member for anchoring the same with extensive bond and bearing in the concrete.

3. In a concrete slab construction, the combination with a supporting column of reinforcing members diverging from the axis of the column, each of said members having a reverse bend near the column and presenting a tension reinforcement portion near the upper surface of the slab, and a prolonged compression reinforcement portion near the lower surface of the slab.

4. In a concrete slab construction, the combination with a supporting column of

reinforcing members diverging from the axis of the column, each of said members having a reverse bend near the column and presenting a portion near the upper surface of the slab and a portion near the lower surface of the slab extending across and serving as a compression reinforcement for the juncture of the slab with the column; and other reinforcing members arranged 10 transversely of said diverging members and circumferentially of said column axis.

5. In concrete construction, the combination with supporting columns, of an intermediate slab, reinforcing members in said 15 slab diverging from the axis of the column, each of said members having a reverse bend near the column and presenting tension and compression portions near the upper and lower surfaces respectively of the slab and 20 prolonged away from said column; other reinforcing members arranged transversely of said diverging members and circumferentially of said column axis; a series of reinforcing members diverging from a central 25 point in said slab between said columns and reinforcing members arranged transversely of said diverging members and circumferentially of said central point.

6. In concrete construction, the combination with supporting columns, of an intermediate slab, reinforcing members in said 30 slab diverging from the axis of the column, each of said members having a reverse bend near the column and presenting a portion 35 near the upper surface of the slab, and a portion near the lower surface of the slab extending across and serving as a compression reinforcement for the juncture of the slab with the column; other reinforcing

members arranged transversely of said diverging members and circumferentially of said column axis; a series of reinforcing members diverging from the central point in said slab between said columns and reinforcing members arranged transversely of said diverging members and circumferentially of said central point. 40 45

7. In a concrete slab construction, the combination with supporting columns, of an intermediate panel, a series of reinforcing members near the upper surface of the slab diverging from the axis of the column, means for anchoring the inner ends of said members comprising an anchoring ring with which the bent ends of the members engage, the bent end of each member being prolonged adjacent the lower surface of the slab to serve as compression reinforcement, other reinforcing members arranged transversely to said diverging members and circumferentially of said column axis, 50 a series of reinforcing members diverging from a central point in the panel and arranged near the lower surface of the slab, means for anchoring the inner ends of said 55 last named members comprising an anchoring ring engaging the bent over ends on the members, and reinforcing members arranged transversely to the diverging members. 60 65

In testimony whereof, I have signed my name to this specification, in the presence of two subscribing witnesses.

EDWARD SMULSKI.
